UNITED STATES PATENT OFFICE.

CLAUDE A. CONOVER, OF NEWBURGH, NEW YORK.

PENCIL SHARPENER.

Application filed March 16, 1922. Serial No. 544,203.

To all whom it may concern:

Be it known that I, CLAUDE A. CONOVER, a citizen of the United States, and a resident of Newburgh, in the county of Orange and State of New York, have invented a new and Improved Pencil Sharpener, of which the following is a full, clear, and exact description.

This invention relates to pencil sharpeners and has for an object to provide an improved construction wherein an ample cutting surface is presented while the lead of the pencil is protected against breakage.

Another object of the invention is to provide a pencil sharpener in which the cutting member is arranged in a tube capable of receiving a pencil retaining fitting.

A further object of the invention is to provide a pencil sharpener formed in two principal parts connected together in a suitable manner and formed so as to be usable alone or in connection with a supporting tube.

In the accompanying drawing—

Figure 1 is a side view with certain parts broken away disclosing one embodiment of the invention.

Figure 2 is a plan view of the cutting structure shown in Figure 1.

Figure 3 is an edge view of the structure shown in Figure 2.

Figure 4 is a view similar to Figure 2 but looking at the same from the opposite side.

Figure 5 is a sectional view through Figure 1 approximately on line 5—5.

Figure 6 is a sectional view through the cutter shown in Figure 2 but with the parts welded together.

Figure 7 is a view similar to Figure 6 but showing the parts riveted together instead of welded.

Referring to the accompanying drawing by numerals, 1 indicates a tube of a proper size to receive the cutting structure 2 as shown in Figure 2. The tube 1 is provided with a restricted end 3 which may receive a rubber eraser or other implement as desired while the open end is designed to receive a pencil similar to pencil 4 whenever it is desired to sharpen the same and when the sharpener is not being used a clip or fixture 5 may be inserted into the open end of the tube. The clip 5 is provided with a rounded face 6 designed to snugly fit the open end of the tube 1 and with resilient

grips or clamping members 7 and 8 for gripping the pencil 4. It will thus be seen that when the parts are arranged as shown in Figure 1, the device may be used as an ordinary pencil with a properly pointed lead at one end and an eraser at the opposite end. Whenever it is desired to sharpen the pencil, the clip 5 is removed and the pencil forced into the tube 1 and rotated as it is moved therein. This will cause the cutting member 2 to perform the desired cutting operation.

The cutting structure 2 is formed of two principal parts, namely, the part or section 9 and the part or section 10. These parts are identical except that the part or section 10 is cut away at 11 whereby the shavings may freely escape and the lead of the pencil may have a free opening. The respective parts 9 and 10 are made from flat pieces of metal pressed with tapering portions 12 and 13, portion 12 being cut away to form the opening 11 while one edge of portion 13 is bent slightly inwardly and sharpened at 14 for forming a cutting edge.

In the form of the invention shown in Figures 2 to 5, the plate 15 from which the tapering portion 13 is pressed is positioned with the edge in one turned over flange 16 and part of one edge of the turned over flange 16'. The flange 16' is preferably formed integral with the plate 17 from which the pressed out portion 12 is formed, is positioned as shown in Figures 4 and 5 and acts to hold the two parts or sections 9 and 10 firmly together. If desired, the parts could be welded, as for instance, along the line 18 (Fig. 6) or could be spot-welded at different places. Also, the parts might be riveted together by suitable rivets 19 as shown in Figure 7. It will be understood that a large number of other ways could be provided for securing these parts together and the same results obtained, namely, a strong, simple structure adapted to properly cut the wood of a pencil and taper the lead without breaking the lead.

It will be noted that the cutting edge 14 extends from near the large end 20 of the sections 9 and 10 entirely across the cut-away portion 11 in order that the lead will be properly tapered in addition to properly cutting the wood of the pencil. If desired, the cutting structure 2 may be used separately, or the form shown in Figures 2 to 5,

or may be forced into the tube 1 and used in connection therewith. When this latter course is followed, the tube 1 is provided with a slot 21 opposite the cutting edge or 5 knife 14 whereby the parts removed from the pencil may be freely discharged. The cutting structure 2 may be held in the tube 1 merely by friction or may be secured therein by solder or other means as the cutting 10 structure 2 is made from comparatively thin, high grade steel which would ordinarily be used in a protecting tube similar to tube 1, which tube may be easily mounted on the end of a pencil similar to pencil 15 4 or may be connected therewith through the clip 5.

Other slight changes and modifications might be made without departing from the spirit of the invention provided the cutting 20 structure is formed substantially as shown in Figures 1 to 7 inclusive.

What I claim is:—

1. A pencil sharpener comprising, a cutting structure formed with a sharpened 25 portion acting as a cutting knife, and a centrally positioned web substantially rectangular, and a tube for receiving said cut-

ting structure, said web fitting against the walls of the tube whereby the cutting structure is properly centered in the tube. 30

2. A pencil sharpener comprising a cutting structure formed in two parts, each part being constructed of sheet metal and having a tapering portion arc-shaped in cross section, and a web extending from the 35 edges thereof, and means for securing said webs together, one of said tapering portions being cut off at the small end while the opposite tapering portion having one edge separated from its web and sharpened, 40 said sharpened edge being bent inwardly to produce a cutting knife.

3. A pencil sharpener formed in two sections, each section having a tapering semi-tubular structure, and a web extending 45 from the edges of said structures, means for securing said webs together, one of said tapering structures being cut off at the small end for presenting an opening while the opposite tapering structure is bent inwardly 50 and formed with a cutting edge extending across said opening.

CLAUDE A. CONOVER.
